LUBRICATING MECHANISM FOR SEWING-MACHINE LOOP TAKERS

William C. Van Ness, Lynbrook, N. Y., assignor to
The Singer Manufacturing Company, Elizabeth, N. J., a corporation of New Jersey

Application May 17, 1945, Serial No. 594,347

7 Claims. (Cl. 112—256)

1

This invention relates to devices for lubricating the thread-carrier raceways of sewing machine loop-takers and, more particularly, the thread-carrier raceways of loop-takers of the horizontal-axis rotary hook type.

The present invention is an improvement on the lubricating device forming the subject of a pending patent application of C. A. Kessler, Serial No. 583,092, filed March 16, 1945, and has for its primary object to insure proper lubrication of the thread-carrier raceway of a sewing machine loop-taker, regardless of substantial variations in the levels of the lubricant supply.

More specifically, it is an object of the invention to provide a lubricant circulating system for maintaining delivery to the loop-taker raceway of an adjustably regulated quantity of lubricant under conditions in which a minimum of lubricant need be drawn from a source of supply.

With these and other objects in view, as will hereinafter appear, the invention consists in the devices, combinations and arrangements of parts hereinafter described in connection with the accompanying drawings, which illustrate a preferred embodiment of the invention and in which:

Fig. 1 represents a vertical longitudinal section of a portion of the bed-plate of a sewing machine containing the present improvement. Fig. 2 represents a vertical section of the loop-taker shaft and its bushing; the section being taken substantially on the line 2—2 of Fig. 1. Fig. 3 represents a longitudinal section of the loop-taker shaft mechanism; the section being taken substantially on the line 3—3 of Fig. 2 and the loop-taker being shown as partly broken away. Fig. 4 represents a section similar to Fig. 2, but taken substantially on the line 4—4 of Fig. 1. Fig. 5 is an end elevation of the inner end of the loop-taker shaft bushing and pinion.

The sewing machine in part illustrated in the drawings has a work-supporting bed-plate 10 provided with a throat-plate 11 having a needle-aperture 12. The bed plate 10 has depending walls formed to provide a gear-casing and a main oil-reservoir chamber 13 having a bottom closure-plate 14 suitably secured to said walls.

Secured by a screw 15 in a wall 16 of the gear-casing, is a bushing 17 in which is journaled a horizontally disposed rotary actuating shaft 18. The shaft 18 may be rotated by any suitable driving connections therewith. Secured to the end of the shaft 18 within the oil-reservoir chamber 13 is the hub of an internal driving gear 19.

In mesh with the teeth of the internal gear 19 is a pinion 20 having its horizontal axis of rotation preferably lying in a vertical plane containing the axis of rotation of the driving shaft 18. The ratio of the internal gear 19 and pinion 20 is such that said pinion rotates twice for each

rotation of the gear 19. The pinion 20, which is also disposed in the oil-reservoir chamber 13, is carried by one end of a horizontally disposed loop-taker shaft 21 and is preferably integral with said shaft. Secured by screws, as 22, upon the opposite end of the shaft 21 is the hub 23 of a rotary-hook form of loop-taker 24. The loop-taker 24 has the usual cup-shaped body which is provided in its cylindrical side wall with a raceway 25 for the peripheral bearing-rib 26 of a thread-carrier 27 journaled in the loop-taker; said thread-carrier 27 being restrained, in any usual or suitable manner, against rotation with the loop-taker. The loop-taker shaft aperture in the hub 23 of the loop-taker is closed by a disk 28 set into the bottom wall 29 of the loop-taker; the loop-taker being, as usual, mounted upon the shaft 21 so that the end of said shaft is spaced from the disk, whereby an oil-collecting recess 30 is provided in the loop-taker. Connecting the oil-collecting recess 30 and the raceway 25 is an angular lubricant-duct 31 provided in the body of the loop-taker.

The loop-taker shaft 21 is rotatably journaled in two horizontally spaced bearing-sleeves 32 and 33, which sleeves are suitably secured in the longitudinal opening 34 of a bushing 35. The sleeve 32 forms a bearing for the shaft 21 adjacent the loop-taker 24 and the sleeve 33 forms a bearing for said shaft adjacent the pinion 20; the spacing of said sleeves providing a lubricant-collecting cavity in the bushing-opening 34 between the sleeves. The bushing 35 is secured in a horizontal opening, provided in the wall 36 of the gear-casing, by a screw 37 which enters a groove 38 formed in the outer face of the bushing to extend lengthwise thereof. The described construction provides for assembly of the loop-taker shaft 21 and its bearing-sleeves 32, 33 in the bushing 35 as a unit construction, as well as for axial adjustment of the loop-taker 24 by endwise adjustment of the bushing 35 in the frame-wall 36.

One end portion of the bushing 35, extending into the oil-reservoir 13, is partly cut away to form a segmental extension 35' which partly surrounds the pinion 20 and affords the necessary clearance for engagement of the driving-gear 19 with the pinion 20. Secured by screws 39 in the bushing-extension 35' is a segmental block 40 which serves to hold the loop-taker shaft 21 against endwise movement in its bearings; a washer 41 being preferably interposed between the pinion 20 and the bearing-sleeve 33.

The bushing 35 is provided in its upper face with an oil-collecting cavity 42 which, in part, is disposed in the oil-reservoir chamber 13; said cavity comprising an auxiliary lubricant-reservoir. The cavity 42 is supplied with oil, during the operation of the machine, by the oil-throwing

action of the driving-gear 19 which dips into a supply of oil in the main reservoir or chamber 13. Leading downwardly from the lower portion of the inclined bottom wall of the oil-collecting cavity 42 is an upwardly enlarged reservoir outlet oil-duct 43 provided in the bushing 35 and disposed in vertical alinement with an inlet oil-duct 44 provided radially in the bearing-sleeve 33.

The loop-taker shaft 21 is exteriorly provided, in the portion of the shaft within the sleeve 33, with a spiral groove 45 which terminates at one end in a radial aperture 46 of the shaft 21. The lead of the spiral groove 45 is such as to feed oil from the sleeve-duct 44 to the inlet shaft-aperture 46 upon operation of the machine. Furthermore, the pitch of the spiral groove 45 is preferably sufficiently steep to insure that oil is forced into the shaft-aperture 46 under a pressure which is greater than the centrifugal force action which would oppose entrance of oil into the shaft-aperture 46. The shaft 21 has a longitudinal bore 47 extending from the loop-taker end of the shaft to a point adjacent the pinion 20, and the shaft-aperture 46 communicates with the shaft-bore 47 intermediate the ends of said bore. It will therefore be understood that during the operation of the machine, oil is not only fed or pumped under pressure into the shaft bore 47, but oil pressure is also built up in said shaft bore.

Threaded into the loop-taker end of the shaft 21 is a hollow cartridge 48 having its head end provided with a screw-driver slot. The cartridge 48 is internally threaded to retain therein one end of an oil-filtering wick 49 which extends a substantial distance into the shaft-bore 47. At the head end of the cartridge, the internally threaded portion thereof terminates in an axial cartridge-aperture 50 of reduced size and which is open to the oil-collecting recess 30 of the loop-taker.

Adjacent the inner end of the shaft-bore 47 and at the side of the sleeve oil-duct 44 opposite the radial shaft-aperture 46, the shaft 21 is radially provided with an outlet shaft-aperture 51 which connects the shaft-bore 47 with an annular groove 52 provided internally of the bearing-sleeve 33. As illustrated in Figs. 2 and 3 of the drawings, the bearing-sleeve 33 is radially provided with a discharge or outlet duct 53 extending at an upward inclination from the sleeve-groove 52. The bushing 35 is also radially provided with an angular discharge duct 54 communicating with the duct 53 of the bearing-sleeve; said duct 54 terminating in the auxiliary reservoir 42 and forming a lubricant-inlet duct of the reservoir. The shaft-aperture 51, sleeve-groove 52 and communicating outlet ducts 53 and 54 together comprise a pressure-relief port for the oil pumped into the shaft-bore 47 by the spiral groove 45 of the shaft.

In order to provide means for regulating the effectiveness of the described pressure-relief port, the bushing 35 is longitudinally provided with a stepped bore 55 having a reduced portion 55' thereof intersecting the bushing-duct 54. Threaded into the bushing-bore 55, for endwise adjustment, is a shouldered valve-rod 56 disposed substantially parallel to the loop-taker shaft 21 and having its inner end conically shaped to provide a needle-valve 56'. By endwise adjustment of the valve-rod 56, the position of the needle valve 56' may be regulated to vary the size of the pressure-relief duct, or completely to close said duct.

The shaft-bearing face of the sleeve 33 is, of course, directly lubricated by the oil supplied through the sleeve oil-duct 44 and also, in part, by the oil discharged through the radial shaft-aperture 51. In order to insure adequate lubrication of the shaft-bearing face of the sleeve 32, said sleeve is provided in its inner face with a groove 57 extending lengthwise of the sleeve. Lying in the groove 57 is one end portion of a wick 58, of which the other end extends into contact with the inner bottom face of the bushing 35 in the bushing-opening 34 between the sleeves 32 and 33. Some excess oil fed by the spiral groove 45 will be discharged into the bushing-opening 34 between the bearing-sleeves 32, 33. In this manner, oil is supplied to the wick 58 and is fed thereby to the bearing-face of the sleeve 32. The portion of the shaft 21 within the sleeve 32 is exteriorly formed with a spiral groove 59 having a lead such as to feed excess oil back into the bushing-opening 34 between the bearing-sleeves.

The quantity of oil which may collect in the bushing-opening 34 is limited by the provision in the bushing 35 of a drain-aperture 60 having its inlet end disposed slightly above the level of the lowest portion of the opening 34. The aperture 60 is connected with the external bushing-groove 38, of which one end extends into the oil-reservoir chamber 13.

In order more quickly to create a pressure of lubricant in the shaft bore 47, it is preferred to restrict the diametral size of the bore, between the wick 49 and the inner end of said bore, by inserting therein a rod 61. Obviously, this may also be accomplished by correspondingly forming the shaft-bore.

From the foregoing description, it will be understood that, during the operation of the machine, oil is continuously pumped under pressure into the loop-taker shaft bore 47 and that the oil is pressure-fed through the oil-filtering wick 49 and through the restricted cartridge-aperture 50 into the loop-taker recess 30, from which recess the oil is delivered through the lubricant-duct 31 to the raceway 25 of the loop-taker. By endwise adjustment of the valve-rod 56, the pressure of the oil within the loop-taker shaft bore 47 may be regulated to a nicety to meet the requirements of different operating speeds and different kinds of work. To provide for access to the head end of the valve-rod 56, it is simply necessary to withdraw the thread-case 62 from its carrier 27 which is journaled in the loop-taker; the usual construction of the bottom walls of the thread-case carrier 27 and of the loop-taker 24 being such as to permit of use of a screw-driver for adjusting the valve-rod. The present construction, therefore, provides for adjustment of the oil-pressure in the shaft-bore without removal of the loop-taker from the shaft 21.

The quantity of oil supplied to the loop-taker raceway 25 is usually small in comparison with the quantity of oil bled from the shaft-bore 47 through the pressure-relief conduit. By returning the oil through the pressure-relief conduit to the auxiliary reservoir 42, there is thus provided a lubricant-circulating system requiring a minimum of additional oil to maintain constant the quantity of oil delivered to the loop-taker raceway. This minimum quantity of additional oil will be supplied from the main reservoir 13, even when the level of the supply of oil in the main reservoir is very low.

Having thus set forth the nature of the invention, what I claim herein is:

1. In a sewing machine, a rotary shaft having a longitudinal bore and having radial inlet and outlet apertures in the wall thereof, a loop-taker carried by said shaft and having a thread-carrier raceway, lubricant-conducting means connecting the bore of said shaft and said raceway, a lubricant-reservoir disposed above the level of said shaft, means effective upon rotation of said shaft for supplying lubricant under pressure from said reservoir through said inlet aperture and into said bore of the shaft, a pressure-relief duct leading from the outlet aperture and connected with said reservoir for re-circulation of said lubricant, and means for regulating the flow of lubricant through said pressure-relief duct.

2. In a sewing machine, a rotary shaft having a longitudinal bore and having radial inlet and outlet apertures in the wall thereof, a loop-taker carried by said shaft and having a thread-carrier raceway, lubricant-conducting means connecting the bore of said shaft and said raceway, a main lubricant-supply reservoir, an auxiliary lubricant-reservoir connected with the bore of said shaft, means for delivering lubricant from said main reservoir to said auxiliary reservoir, pump means effective upon rotation of said shaft for supplying lubricant under pressure from said auxiliary reservoir through said inlet aperture and into said bore of the shaft, a pressure-relief duct leading from the outlet aperture and terminating in said auxiliary reservoir, and means for regulating the flow of lubricant through said pressure-relief duct.

3. In a sewing machine, a rotary shaft provided with a longitudinal bore and having radial inlet and outlet apertures in the wall thereof; a loop-taker carried by said shaft and having a thread-carrier raceway; lubricant conducting means connecting the bore of said shaft and said raceway; a main lubricant reservoir; an auxiliary lubricant reservoir disposed above the level of said shaft; a lubricant circulating system for draining lubricant from said auxiliary reservoir, for pumping lubricant into said bore, and for discharging lubricant out of said bore and through said outlet aperture into said auxiliary reservoir; means for regulating the flow of lubricant in said circulating system; and means effective during the operation of said machine for supplying additional lubricant to said auxiliary reservoir.

4. In a sewing machine, a rotary shaft provided with a longitudinal bore and having radial inlet and outlet apertures, a loop-taker carried by said shaft and having means for receiving lubricant from said bore, a main lubricant reservoir, an auxiliary lubricant reservoir, means for supplying lubricant from said main reservoir to said auxiliary reservoir, and a lubricant circulating system for draining lubricant from said auxiliary reservoir, pumping it through said inlet aperture into said bore, and discharging it through said outlet aperture and back into said auxiliary reservoir.

5. In a sewing machine, in combination, a frame affording a main oil reservoir; a drive shaft journaled in said frame; a bushing secured in said frame and provided with oil-inlet and oil-outlet apertures, and with an auxiliary oil reservoir located above said main reservoir; a sleeve secured in said bushing and provided with oil-inlet and oil-outlet apertures communicating with the corresponding apertures of said bushing; a

loop-taker shaft rotatably journaled in said sleeve and provided with a longitudinal bore and with radial oil-inlet and oil-outlet apertures communicating with the corresponding apertures of said sleeve; a loop-taker carried by one end of said shaft and provided with a thread-carrier raceway having oil-conducting connections with the bore of said loop-taker shaft; means including a member secured on said drive shaft for conveying oil from said main reservoir to said auxiliary reservoir; a completely organized oil-circulating system embodied in said bushing for transmitting oil from said auxiliary reservoir through said oil-inlet apertures, through the bore in said loop-taker shaft, through said oil-outlet apertures and back to said auxiliary reservoir; and valve means embodied in said system to maintain a back-pressure in the bore of said loop-taker shaft to force oil to said raceway in said loop-taker.

6. In a sewing machine having a frame provided with a horizontally disposed opening, a rotary shaft journaled in said frame, and a driving gear secured upon one end of said shaft; a loop-taker unit removably secured in said opening and comprising a bushing fitted in said opening, a rotary loop-taker shaft journaled in said bushing and provided with an axial bore, a loop-taker carried by one end of said loop-taker shaft and provided with a thread-carrier raceway, a driven gear on the opposite end of said loop-taker shaft adapted to engage said driving gear when said loop-taker unit is inserted into said opening in the frame, lubricant-conducting means connecting said bore with said raceway, a lubricant reservoir formed in said bushing above said loop-taker shaft, and a lubricant circulating system carried wholly by said bushing for forcing oil from said reservoir into the bore in said loop-taker shaft and from said bore back into said reservoir.

7. In a sewing machine having a frame provided with a horizontally disposed opening, a rotary shaft journaled in said frame, and a driving gear secured upon one end of said shaft; a loop-taker unit removably secured in said opening and comprising a bushing fitted in said opening, a rotary loop-taker shaft journaled in said bushing and provided with an axial bore, a loop-taker carried by one end of said loop-taker shaft and provided with a thread-carrier raceway, a driven gear on the opposite end of said loop-taker shaft adapted to engage said driving gear when said loop-taker unit is inserted into said opening in the frame, lubricant-conducting means connecting said bore with said raceway, a lubricant reservoir formed in said bushing above said loop-taker shaft, a lubricant circulating system carried wholly by said bushing for forcing oil from said reservoir into the bore in said loop-taker shaft and from said bore back into said reservoir, and valve means embodied in said system for maintaining a back-pressure in the bore in said loop-taker shaft.
